(57) **CLAIM**

The ornamental design for a computer having a drive carrier, as shown and described.

DESCRIPTION

FIG. 1 is a perspective view of the design for the computer having a drive carrier, wherein broken lines illustrate environmental features including the drive disposed in the drive carrier, and the computer in which the drive carrier removably supports the drive; and,

FIG. 2 is a partial front elevational view of the design for the computer having a drive carrier of FIG. 1, wherein broken lines illustrate environmental features including the drive disposed in the drive carrier, and the computer in which the drive carrier removably supports the drive.

In these drawings, the solid lines illustrate the claimed ornamental design, whereas the broken lines illustrate environmental features that form no part of the claimed ornamental design.
